Des. 197,981
Patented Apr. 14, 1964

197,981

COMPOTE OR THE LIKE

Willie Mae Miller, Lake Leelanau, Mich.

Filed Oct. 17, 1963, Ser. No. 77,020

Term of patent 14 years

(Cl. D44—10)

FIG. 1 is a perspective view of a compote showing my new design.

FIG. 2 is a top plan view on a reduced scale; and

FIG. 3 is a cross-sectional view taken on line 3—3 of FIG. 2, on the same scale as FIG. 2.

I claim:

The ornamental design for a compote or the like, substantially as shown.
